C. J. WITZEL

WRENCH

Filed Sept. 27, 1921

Inventor:

C. J. Witzel

By his Attorneys:

Weed & Gray

UNITED STATES PATENT OFFICE.

CHARLES J. WITZEL, OF BROOKLYN, NEW YORK.

WRENCH.

Application filed September 27, 1921. Serial No. 503,513.

To all whom it may concern:

Be it known that I, CHARLES J. WITZEL, a citizen of the United States, residing at Brooklyn, in the county of Kings and State of New York, have invented certain new and useful Improvements in Wrenches, of which the following is a specification.

This invention relates to wrenches, an object thereof being to provide an improved wrench provided with the usual adjustable gripping jaws and having positive means for preventing derangement or disturbance of any predetermined adjustment thereof, particularly as may be likely to result from the manipulation of the device.

A further object of this invention is to provide an improved wrench having a shiftable jaw and the usual operating means therefor, such as an operating screw, and provided with means, such as for example, a resilient friction device for restricting or retarding the free rotary movement of the screw, thereby tending to minimize the possibility of inadvertent derangement of the adjustment of the jaws.

A further object of this invention is to provide an improved wrench having the usual spur gears or pinions for operating the parts, one thereof adapted to be shifted out of mesh with the other, thereby preventing operation of the parts. In the present instance, for accomplishing this purpose, the operating handle is mounted in slidable or telescopic manner and is adapted to be shifted to unmash the gears. In pursuance of the foregoing, it is also the purpose of this invention to provide preferably a duplex supporting sleeve for the operating screw and spaced from the gears, the same having means for locking or retaining a gear in unmashed or inoperative position.

A further object of this invention is to provide a wrench having the usual relatively adjustable jaws and wherein the construction is such that the jaws may be positively adjusted one relatively to the other and independently of the operating mechanism thereby to vary the range of movement or travel or the throw thereof.

Other objects of this invention will appear in the following description thereof, reference being had to the accompanying drawing forming a part of this specification, wherein like reference characters indicate corre-

sponding parts in the several views and wherein Fig. 1 is a side view partly broken away and partly in section illustrating a form of my invention, and the operating parts in one position; Fig. 2 is a similar view illustrating the operating parts in another position; Fig. 3 is a detailed perspective view of one of the jaws; Fig. 4 is a detailed perspective view of the duplex supporting sleeve; Fig. 5 is a detailed perspective view of the operating handle; and Fig. 6 is a detailed perspective view of the operating screw.

In the preferred form herein shown and described, I have illustrated my invention as applied to a wrench having a movable and a stationary gripping jaw, but it is of course understood that the same may be applied to any preferred type of wrench, such as one having simultaneously movable jaws. Referring to the drawing, it will be seen that my improved wrench comprises a stationary gripping jaw 10, having an integrally formed rearwardly extending angular shank 11. This shank terminates in a cylindrical extension or stem 12. Adapted to be mounted upon the stem 12 is a duplex supporting or clamping sleeve 13 having an opening 14 therethrough for slidably receiving the stem 12. The sleeve 13 may be secured to the stem as by means of a set screw 17 inserted in the opening 15 of the sleeve and cooperating with an opening 16 formed in the stem.

For the purpose of manipulating the device, an operating handle 18 having its outer surface fluted or otherwise formed is provided, the same having a bore 19 adapted to be telescoped to the rear end of the cylindrical stem 12 for predetermined slidable movement relatively thereto. At its inner end the handle 18 carries a spur gear or pinion 20 preferably formed integrally therewith. This gear is provided with an annular flange 21, and the same together with the gear 20 are provided with internal threads 22 adapted to cooperate with a threaded shoulder 23 integrally formed from the sleeve 13. The annular flange 21 forms a shoulder over which is secured a washer 24 extending beyond the periphery of the gear. A spring 19^a is inserted in the bore 19 impinging against the inner end of the stem 12, the same resiliently tending to maintain the handle 18 and gear 20 in the

position illustrated in Fig. 1. The handle, when shifted forwardly, will compress the spring, the latter thus positively tending to force the parts to operative position.

5   Mounted for shiftable movement upon the angular shank 11 is a movable gripping jaw 25 tapped at 26 to receive the threaded end of the screw 27, the latter having a rearwardly extending non-threaded cylindrical portion 28. The supporting sleeve 13 is bored at 29 so as to fit over the cylindrical portion 28 of the operative screw and is held in position by means of a washer 30 secured to the operating screw. The 10 latter may, if desired, be formed as an integral part of the operating screw. A set screw or pin 32 is provided for retaining the duplex sleeve 13 in position against the washer or shoulder 30. The operating screw 27 is preferably squared at its outer end 31 and a spur gear 33 or pinion having a square bore is secured to the portion 31 and held in position by means of a pin 34.

In order to restrict or retard the normally 25 free rotary movement of the operating screw 27 and thereby minimize the danger of disturbing a predetermined adjustment of the gripping jaws, suitable automatic means in the form of a resilient frictional device is provided for accomplishing this purpose. The sleeve 13 is recessed at 35 at right angles and transversely to the bore 29, and in assembling the sleeve and operating screw the spring 36 is forced into the 30 upper part of the recess 35 so as to impinge against the annular part 28 of the screw and to be held under predetermined tension between the same and the upper part of the recess. Thus, the spring 36 will exert constant frictional pressure upon the operating screw, and although not preventing the rotation and operation of the same, it will tend to restrict and prevent unintentional operation of the screw.

45   In the operation of my improved wrench, it will be readily observed that the operating parts may be disconnected and rendered ineffective at any desired time and without dismounting the device, disuniting or removing any of the parts. Assuming that the gripping jaws 10 and 25 have been adjusted from the position shown in Fig. 1 to the position shown in Fig. 2 by rotating the handle 18 and thereby causing the gear 20 to rotate the gear 33 together with the operating screw 27, resulting in the shifting of the movable jaw 25 relatively to the stationary jaw 10, the handle 18 may be shifted lengthwise of the stem 12 toward the duplex sleeve 13 and the flange 21 quickly threaded upon the threaded portion 23 of the sleeve. By virtue of this operation the gears 20 and 33 will be disconnected or unmeshed, and as a result, the danger of deranging or disturbing the ad-

justment of the jaws on manipulating the handle 18 will be eliminated. As will be seen in Fig. 2, the operating handle may be firmly screwed upon the threaded extension 23, thereby rigidly retaining these parts together and forming a rigid manipulating handle. When the device is being used with the adjustment as shown in Fig. 2, the spring 36 is effective to prevent inadvertent or accidental rotation of the operating screw 27. When it is desired to change the adjustment of the jaws from the position shown in Fig. 2 the handle 18 will be rotated to release the same from the threaded part 23 and thereupon shifted rearwardly until the gear 20 meshes with the gear 33. The washer 24 acts as a guide or stop for alining the gears and preventing excessive rearward shifting of the operating handle, this washer, as shown in Fig. 1, abutting against the inner edge of the gear 33.

It will be further noted that I have provided means for adjusting or varying the range of movement or the throw of the gripping jaws 10 and 25. This is accomplished merely by removing the set screw 17 and adjusting the same in any one of several apertures 16 formed in the stem 12. In accomplishing this it will be seen that upon shifting the supporting sleeve 13 rearwardly or forwardly all of the operating parts will in like manner be shifted simultaneously relatively to the fixed or stationary jaw 10. Although I have described my invention in its preferred form, it is to be understood that I do not limit myself to the construction herein shown and described, but may make all changes coming within the scope of the appended claims.

I claim as my invention:

1. As an article of manufacture, a wrench comprising a pair of gripping jaws, means for operating the same, and including means shiftable relatively to said gripping jaws for rendering said operating means inoperative, and means for shifting said shiftable means.

2. As an article of manufacture, a wrench comprising a pair of gripping jaws, rotatable means for operating the same, and resilient and means for automatically restricting the normal rotative movement of said last means and operative transverse to the axis of rotation thereof.

3. As an article of manufacture, a wrench comprising a pair of gripping jaws, rotatable means for operating the same, and automatic friction means for restricting the normal rotative movement of said last means and operative transverse to the axis of rotation thereof.

4. In a wrench the combination of a pair of relatively adjustable gripping jaws, a pair of cooperating gears for operating the same, and a gear shift mechanism therefor.

5. In a wrench the combination of a pair of relatively adjustable gripping jaws, operating means therefor including a pair of cooperating gears, means for shifting one of said gears relatively to the other thereby to unmesh the same and means for retaining said gears in said relation. 10
6. As an article of manufacture, a wrench comprising a pair of relatively adjustable gripping jaws, operating means therefor, and means for varying the range of operative movement of said jaws while maintaining the engagement of said operating means. 15
7. In a wrench the combination of a pair of relatively adjustable gripping jaws, operating means therefor including a pair of cooperating gears, and means shiftable relatively to said jaws for disconnecting said 20 gears.
8. As an article of manufacture, a wrench comprising a pair of relatively adjustable gripping jaws, operating means therefor and including a pair of cooperating gears, 25 means for disconnecting said gears, and means for retaining said gears in such relation and comprising a normally stationary member adapted to be connected to one of said gears.
9. As an article of manufacture, a wrench comprising a pair of relatively adjustable gripping jaws, operating means therefor and including a pair of cooperating gears, 30 means comprising a shiftable handle for shifting one of said gears relatively to the other thereby to unmesh the same, and means for retaining said gears in such relation, said last means comprising a normally stationary member adapted to be connected to one of said unmeshed gears. 40
10. As an article of manufacture, a wrench comprising a pair of relatively adjustable gripping jaws, means for operating the same, and means for varying the range 45 of operative movement of said jaws independently of said operating means, said means comprising a releasable element adapted to permit one of said jaws and certain of said operating means to be simultaneously adjusted relatively to the other jaw. 50
11. As an article of manufacture a wrench comprising a pair of relatively adjustable jaws, an operating screw and a rearwardly extending shank therefor, a pair of gears, one thereof carried by said screw, and supporting means for said screw having a part thereof carried by said shank and spaced from a gear to permit shiftable movement 55 thereof. 60
12. As an article of manufacture, a wrench comprising a pair of relatively adjustable jaws, an operating screw therefor, a pair of gears, one thereof carried by said screw, a duplex supporting sleeve adapted 65
- to receive said screw and normally spaced from said gears, and means for shifting one of said gears relatively to said sleeve. 70
13. As an article of manufacture, a wrench comprising a pair of relatively adjustable jaws, an operating screw therefor, a pair of gears, one thereof carried by said screw, a supporting sleeve adapted to receive said screw, and resilient means carried by said sleeve and engaging said screw 75 for retarding the rotary movement thereof. 80
14. As an article of manufacture, a wrench comprising a pair of relatively adjustable jaws, an operating screw therefor, a pair of gears, one thereof carried by said screw, a supporting means adapted to receive said screw, and means for adjusting said means relatively to one of said jaws. 85
15. As an article of manufacture, a wrench comprising a pair of gripping jaws, 90 one thereof having a rearwardly extending shank, a handle slidably mounted upon said shank, a gear carried by said handle, an operating screw for said jaws, a gear carried thereby and cooperating with said first gear, 95 said handle being shiftable to unmesh said gears. 100
16. As an article of manufacture, a wrench comprising a pair of gripping jaws, one thereof having a rearwardly extending shank, a handle slidably mounted upon said shank, a gear carried by said handle, an operating screw for said jaws, a gear carried thereby and cooperating with said first gear, 105 said handle being shiftable to unmesh said gears, and means for limiting the movement of one of said gears relatively to the other. 110
17. As an article of manufacture, a wrench comprising a pair of gripping jaws, one thereof having a rearwardly extending shank, a handle slidably mounted upon said shank, a gear carried by said handle, an operating screw for said jaws, a gear carried thereby and cooperating with said first gear, 115 said handle being shiftable to unmesh said gears, and means for retaining said gears in unmeshed position comprising cooperating spaced threaded members, one thereof carried by a gear. 120
18. As an article of manufacture, a wrench comprising relatively adjustable gripping jaws, operating means therefor, and means for rendering said last means inoperative and including a slideable handle adapted to be connected and disconnected from certain of said operating means. 125
19. In a wrench, the combination of a pair of jaws, one shiftable relatively to the other, means for reciprocating the shiftable jaw and comprising a threaded spindle, a gear carried thereby and a gear in mesh therewith, and a handle connected with said last gear for rotating it and thereby to shift the shiftable jaw, said handle being 130

shiftable thereby to disconnect said gears, and resilient means for opposing such movement.

20. In a wrench, the combination of a pair of jaws, one shiftable relatively to the other, means for reciprocating the shiftable jaw and comprising a threaded spindle, a gear carried thereby and a gear in mesh therewith, and a handle connected with said last gear for rotating it and thereby to shift the shiftable jaw, said handle being shiftable thereby to disconnect said gears, and means for holding said shiftable jaw against movement.
21. In a wrench, the combination of a pair of jaws, one shiftable relatively to the other, means for reciprocating the shiftable jaw and comprising a threaded spindle, a gear carried thereby and a gear in mesh therewith, a handle connected with said last gear for rotating it and thereby to shift the shiftable jaw, said handle being shiftable thereby to disconnect said gears, means for

holding said shiftable jaw against movement, and means for holding said first gear against movement when the gears are disconnected.

22. As an article of manufacture, a wrench comprising a pair of relatively adjustable gripping jaws, operating means therefor, and means for permitting certain of said operating means to be shifted into a plurality of positions thereby to vary the range of operative movement of the jaws.

23. As an article of manufacture a wrench comprising a pair of relatively adjustable gripping jaws, operating means therefor, means for disengaging said operating means and including a handle member shiftable in one direction, and resilient means effective to shift said handle member in the opposite direction.

Signed at Brooklyn, New York, this 23 day of September 1921.

CHARLES J. WITZEL.
